UNITED STATES PATENT OFFICE.

HENRY D. MILES, OF BUFFALO, NEW YORK, ASSIGNOR TO BUFFALO FOUNDRY & MACHINE COMPANY, OF BUFFALO, NEW YORK, A CORPORATION OF NEW YORK.

DRYING APPARATUS.

Application filed June 18, 1925. Serial No. 37,935.

This invention relates to a drying apparatus for desiccating liquids containing solids.

One of the objects of this invention is to mount the drying drum and the means for supplying the liquid to be dried to the drum, removing the dried material from the drum and carrying the finished product from the machine, in such manner that the same form a complete unit and admit of either enclosing the same or uncovering the same by an independent casing which is movable relatively to the drum and the working parts associated therewith but wholly disconnected therefrom and thereby enabling the working parts of the apparatus to be completely exposed for cleaning, inspection, repairing and adjustment and also admitting of using the apparatus either as a vacuum or as an atmospheric drier without disturbing the parts which supply the liquid to the drum, spread the same evenly therein, catch the excess liquid, remove the dried material from the drum and convey the dried product from the apparatus.

Further objects of this invention are to provide a drier having improved means for supporting the casing, moving the same into its opened and closed position and detachably connecting the same with the stationary supporting element of the main frame, also to provide improved means for rotatably supporting the drying drum, and also improved means for supplying the liquid to be dried to the drum, carrying off the excess liquid, removing the dried material from the drum, as will presently appear.

In the accompanying drawings:—

Figure 1, is a vertical longitudinal section of my improved drying apparatus showing the various parts in position for operation.

Figure 2, is a front elevation of the same, on an enlarged scale.

Figure 3, is a fragmentary longitudinal section of the means for adjusting the liquid feeding pan toward and from the underside of the drying drum.

Figure 4, is a side elevation of the apparatus showing the enclosing casing opened so as to uncover the internal parts of the apparatus and permit of thoroughly cleaning and easily inspecting and repairing the same.

Figure 5, is a vertical transverse section of the apparatus, on an enlarged scale, taken on line 5—5, Fig. 1, looking forwardly and showing the parts in their operative position.

Figure 6, is a fragmentary vertical trans-

verse section, on a still larger scale, taken on line 6—6, Fig. 1, and showing the liquid feed pan, the liquid spreader, and the scraper or knife moved into an inoperative position away from the drying drum.

Figure 7, is a fragmentary sectional side elevation of the locking mechanism for detachably connecting the movable part of the enclosing casing with its stationary head and showing the parts in a locked position.

Figure 8, is a fragmentary horizontal section taken on line 8—8, Fig. 1.

Similar characters of reference indicate like parts throughout the several views:—

The main frame or support of this drying apparatus preferably comprises a horizontal longitudinal base or bed 10, a comparatively high main standard 11 rising from the central part of this base, and a comparatively low standard 12 rising from the front part of this base.

Arranged on the upper part of the main standard is a stationary vertical head 13 which forms the front end of the enclosing casing of the vacuum chamber of the apparatus.

The body 14 of the enclosing casing is of cylindrical form and arranged so that its axis is horizontal. The rear end of this body is closed by a rear vertical head 15 permanently connected therewith.

The body and rear head of the casing are movable horizontally toward and from the fixed front head for the purpose of enclosing the internal part of the apparatus when in operation and uncovering the same when access to the same is required for cleaning, inspection, adjustment and repairing.

Various means may be employed for thus moving the body and rear head of the casing, those shown in the drawings comprising two longitudinal tracks or rails 16, 16 mounted on the rear part of the base, supporting wheels or roller 17 pivotally mounted in brackets 18 on the underside of the casing body and running on said rails, a longitudinal gear rack 19 secured to the underside of the casing body, and a gear pinion 20 meshing with the gear rack and secured to a transverse shaft 21 which is journaled horizontally in bearings on the rear end of the base. Upon turning this shaft in one direction or the other by a wrench or handle 22 applied to one end thereof the gear pinion 20 causes the gear rack to move forwardly or backwardly.

and thereby either bringing the casing body and front head together or separating the same.

The front end of the casing body and the fixed front head of the same are detachably connected by a locking device which in its preferred form comprises a coupling ring 23 secured to the front end of the casing body and provided with a laterally projecting circumferential locking flange 24 having a plurality of longitudinal openings 25 arranged in an annular row, a circumferential locking ring 26 engaging with the rear side of the coupling flange 24 and provided with a plurality of key-hole slots each of which has a wide part 27 and a narrow part 28, a plurality of wedges 29 of fork shape mounted on the rear side of the locking ring and each having its tines arranged on opposite sides of the narrow part of one of said key-hole slots, and a plurality of coupling pins each of which has a narrow shank, 30, secured to the periphery of the fixed front casing head and adapted to pass through one of the openings 25 of the coupling ring and the key-hole slot of the locking ring and a wide head 31 arranged at the rear end of the shank and adapted to pass through the opening 25 of the coupling flange and the wide part of the respective key-hole slot and to engage with the rear side of one of the wedges. The locking ring is guided on the casing so as to be capable of circumferential rotation thereon by confining the same between the rear side of the coupling flange 26 and a plurality of guide clips 32 secured to this flange and engaging with the rear side of the locking ring. Rotation of the locking ring in one direction or the other for coupling or uncoupling the casing body and front head is effected in the present instance by a gear segment 33 secured to the locking ring, a gear pinion 34 engaging with this segment and mounted on a shaft 35 which is journaled in a bearing 36 on the flange 26, and a ratchet wrench or handle 37 adapted to fit said shaft in one position of the wrench or the other for actuating said locking ring with a ratchet action either for locking the front head and casing body together or unlocking the same. When the locking ring is turned into a position in which the large or wide part of each of its key-hole slots is in line with an opening 25 of the coupling ring and the enlarged head of one of the coupling bolts, then the body of the casing can be moved fully into its foremost position toward the front casing head during which time the head of each coupling bolt passes through one of the openings 25 and the larger part of the respective key-hole slot. When the parts have been thus assembled the locking ring 26 is moved forward circumferentially by the hand operated shifting mechanism, thereby causing each wedge 29 to engage underneath the front side of the

head of one of the coupling bolts and draw the casing body and front casing head together. Upon reversing the rotary movement of the locking ring the wedges are disengaged from the heads of the coupling bolts and the larger parts of said key-hole slots are brought into line with these heads and the opening 25 of the coupling ring, thereby permitting the casing body to be separated from the fixed front casing head for opening the casing and permitting access to the interior of the same.

In order to produce a tight joint between the front head and body of the casing a gasket or packing ring 38 is interposed between these members, which ring is preferably mounted in a groove on the inner or rear side of the front casing head, as shown in Figure 1.

A vacuum is created within the drying chamber for the purpose of accelerating the drying of the liquid therein and at a lower temperature by exhausting the vapor from this chamber through a vapor outlet 39 formed in the upper part of the fixed casing head and adapted to be connected with any suitable form of exhausting device such as a condenser, a suction blower or fan, or similar means. By connecting the exhausting vapors in this manner the casing can be opened and closed without disturbing the connections between the vacuum chamber and the vapor exhausting device, thereby facilitating cleaning of the same and reducing the cost of operating the apparatus.

Within the vacuum or drying chamber is arranged the drum upon the periphery of which the liquid to be dried is deposited and retained thereon until desiccated and then removed therefrom. This drum has its axis arranged horizontally and comprises a hollow cylindrical body 40, and heads 41, 42 secured to the front and rear ends of the body, thereby forming a heating chamber within the drum which is adapted to receive steam or similar heating medium. This drum is pivotally mounted so as to rotate about a horizontal longitudinal axis by means of trunnions 43, 44, arranged on the front and rear drum heads and journaled in front and rear bearings 45, 46. The front inner or inboard bearing 45 is formed on the front head 13 of the casing and the rear, outer or outboard bearing 46 is formed on the central part of an upright supporting column 47 arranged in the rear part of the drying chamber. This column is supported upon the front head of the casing by an upper horizontal beam 48 arranged lengthwise above the drum and connected at its front end with the rear or inner side of the front casing head while its rear end is connected with the upper end of the supporting column. Below the drum a beam 49 is arranged lengthwise in the drying chamber and connected at its front end with

the inner or rear side of the front casing head while its rear end is connected with the lower end of the supporting column.

By this means the entire weight of the drum and its bearings is supported on the front head of the casing wholly independent of the body and rear head of the casing which permits of moving this body and rear head rearwardly away from the front casing head for exposing the internal parts of the apparatus without in any way disturbing the drum or the means for rotatably mounting the same within the drying chamber.

In order to render the apparatus more rigid and prevent possible disalignment of the drum and its bearings, the rear trunnion 44 is provided with a cylindrical recess 50 in its rear end which is adapted to receive the front end of a staying bar or rod 51, which latter is adapted to be supported at its rear end in a central opening 52 in the rear head of the enclosing casing. This staying rod, shown by dotted lines in Fig. 1, is only used temporarily for stiffening the machine while handling the same and is removed prior to using the machine. These means permit of using the stay rods 51 between the outer end of the drum and the outer head of the casing so as to prevent excessive strains from being put on the trunnions and bearings of the drum while the drier is being transported over railways or water lines. After the drier is installed this temporary equipment is removed as there is no further danger of straining the parts owing to the absence of jolts, jars or shocks. After the removal of the staying bar the recess 50 is covered by a plate 53 to prevent any vapors from lodging therein and also facilitating cleaning the apparatus, and the stay opening 52 is also closed by a cover plate 54 secured to the rear casing head.

A rotary movement may be imparted to the drum from the exterior of the apparatus by any suitable or approved means, those shown in the drawings having been found satisfactory and comprising a prime mover 55 mounted on the front part of the base and preferably consisting of an electric motor, a speed reducing gearing 56 mounted on the front part of the base and connected with the motor, a horizontal intermediate shaft 57 arranged lengthwise, above the motor and speed reducer and journaled in front and rear bearings 58 and 59 on the base, a belt 60 passing around pulleys 61, 62 on the speed reducer and the intermediate shaft, and a gear pinion 63 arranged on the intermediate shaft and meshing with a gear wheel 64 on the front trunnion of the drum, as shown in Figs. 1, 2 and 4.

Steam or other heating agent is introduced into the drum through an inlet pipe 65 extending axially through the front trunnion of the drum while the water of condensation is re-

moved therefrom by a scoop 66 arranged next to the bore of the drum, an outlet conduit 67 arranged in the front trunnion around the inlet pipe therein, an intermediate pipe 68 connecting the scoop with said outlet conduit, 70 and a delivery pipe 69 surrounding said inlet pipe, said inlet and delivery pipes being stationary and said front trunnion turning around the same by rotary joints therebetween.

The milk, or other solid-containing liquid which is to be desiccated, is delivered to the underside of the drum by a feeding pan 70 which is arranged lengthwise below the drum and adapted to contain a bath of liquid into 80 which the lower part of the drum dips and picks up a thin film thereof in passing over the pan. The pan is mounted on a hollow longitudinal shaft or distributing pipe 71 which is journaled at its front and rear ends in 85 bearings 72, 73 on the front casing head and the column 47 and extends forwardly to the exterior of the enclosing casing. This pan is supported on this hollow shaft by arms 74 and liquid is delivered from this shaft to the 90 pan at different points in the length thereof by branch pipes 75. The liquid is supplied to the distributing pipe 71 by a supply pipe 76 projecting axially into the outer end of the former and receiving its supply from any 95 suitable source. The supply pipe 76 is stationary but the distributing pipe is rotatable about its axis for the purpose of raising the feeding pan into its operative position close to the underside of the drum for delivering 100 liquid thereto, as shown in Fig. 5, or lowered into an inoperative position to permit of cleaning the interior of the pan, as shown in Fig. 6.

The distributing shaft together with the 105 feeding pan mounted thereon may be turned for the purpose described above from the exterior of the apparatus by means which preferably comprise a rock arm 176 secured to the outer end of the distributing pipe, a link 110 77 connected with said arm, an adjusting screw 78 connected with said link, and a rotary adjusting screw nut 79 journaled in a bearing 80 on the main standard so as to be held against lengthwise movement and engaging with the thread of said screw nut, as shown in Figures 2 and 3. Upon turning the screw nut 79 in one direction or the other by the handle 81 thereon the feeding pan will be raised or lowered without affecting any other 115 working parts of the machine.

The excess liquid which is not picked up by the drum overflows from the pan and drops into an overflow trough or catch basin 82 which is arranged lengthwise below the pan 125 within the drying chamber and which is preferably formed in the upper side of the lower beam 49 so that the latter performs the dual function of supporting the outboard bearing of the drying drum and also as a receptacle 130

for the surplus liquid which escapes from the feeding pan. The liquid caught by the overflow trough is discharged therefrom to the exterior of the apparatus from the front 5 end of the trough, an outlet opening 83 from which latter it is conducted by a pipe 84 to any suitable place from which it may be again returned to the feeding pan or otherwise disposed of.

10 After the underside of the drum has picked up a film of liquid the latter is carried past a spreader 85 which extends lengthwise of the drum immediately adjacent to the front side of the pan whereby the liquid is spread out 15 evenly and any bubbles therein are broken up so that the liquid desiccates uniformly. This spreader is mounted on a horizontal longitudinal rock shaft 86 which is journaled in front and rear bearings on the front casing 20 head and the internal column and is capable of being moved toward the drum the required extent for properly acting on the liquid film and also away from the drum for convenience in cleaning, this being preferably accomplished 25 by means similar to those for adjusting the feeding pan, and comprising a rock arm 87 connected with the front end of said spreader rock shaft 86 outside of the casing, a link 88 connected with said arm 87, an adjusting rod 89 connected with said link, and a screw nut 90 which receives a screw thread 30 on said rod and which is journaled in a bearing 91 on the main standard but is held against longitudinal movement therein, so 35 that a turning of the screw nut in one direction or the other will move the spreader toward or from the periphery of the drum.

As the film of milk is carried from the spreader upwardly on the corresponding side 40 of the drum to the top thereof and then downwardly on the opposite side of the same it is dried by the heat imparted to the drum by the steam within it, and before this dried film in its descent again reaches the feeding pan 45 it is scraped off from the external surface of the drum on the descending side of the same by a blade or knife 92 engaging with the drum. This knife is mounted on a longitudinal bar 93 which is pivoted at its lower edge 50 by a pintle 94 on the adjacent longitudinal edge of the lower trough beam 49. Adjustment of the knife relatively to the drum is effected by a longitudinal rock shaft 95 arranged below the knife within the drying 55 chamber and journaled at its front and rear ends in bearings 96, 97 on the front casing head and on said column, a plurality of rock arms 98 projecting upwardly from this rock shaft, a plurality of adjustable links 99 connecting said rock arms with said knife bar, a worm segment 100 secured to the front end of said knife rock shaft outside of said casing, a worm 101 meshing with said worm segment, and a shaft 102 journaled in bearings 103 on the main standard and carrying

said worm at one end and provided at its other end with a hand wheel 104 for turning the same. Upon rocking the shaft 95 by these means in one direction or the other the knife is carried into operative engagement with the drum, as shown in Figure 5, or away therefrom to permit of cleaning the same, as shown in Figure 6. As the dried material is removed from the drum the material drops into a conveyor trough which is arranged lengthwise adjacent to the knife within the drying chamber and extends beyond the front end of the enclosing casing. This trough is supported at its rear end on the upright supporting column and at its front part on the front head of the enclosing casing and that part 105 of the same within the casing is open at the top while that part 106 outside of the casing is closed and of cylindrical form and provided at its front end with a downwardly projecting discharge spout 107.

Within this conveyor trough is arranged a screw conveyor 108 the shaft 109 of which is journaled in bearings at the front and rear ends of the conveyor trough and is turned by power applied to the front end of the same in any suitable or approved manner. As the dried material removed from the drum by the knife falls into the conveyor trough the same is carried lengthwise of the latter and discharged from the spout thereof, suitable means being provided to prevent the entrance of air while the dried product is being discharged in order to prevent breaking of the vacuum in the drying chamber.

While the machine is in operation the body of the casing is clamped tightly against the front head of the same so as to preserve the vacuum therein for promoting desiccation of the liquor under treatment.

When shutting down the apparatus after drying such liquids as milk, it is necessary to clean the interior thereof thoroughly in order to prevent any residue therein from becoming foul or rancid and contaminating the next following batch of milk which is to be dried. For this purpose the body of the casing is disconnected from the front head and moved with the rear head backwardly for uncovering the drum and the parts co-operating therewith and thus rendering the same as well as the interior of the movable parts of the casing or housing freely accessible and capable of being thoroughly cleaned and put in the most sanitary condition. The opening up of the drying apparatus for this purpose can be effected easily and quickly inasmuch as only a part of the casing need be moved. This advantage is due to mounting all the internal working parts of the apparatus on the front fixed head of the casing which is carried on the main frame. Moreover in this construction opening up of the casing does not disturb the adjustment of any of the working parts but permits the same to remain in what-

130

ever position the same may be found to work most satisfactorily and thereby avoid readjustment of the parts every time the apparatus has to be cleaned.

5. It will be apparent from the foregoing that in this drier all of the working parts of the apparatus are mounted on a stationary support, particularly the drum, feed pan, overflow trough, spreader, scraper or knife and 10 conveyer, so that these parts are a distinct unit which constitutes a complete drying apparatus by itself and admits of drying material under vacuum by moving the casing over the drying mechanism to enclose the same, 15 and also admits of using this apparatus as an atmospheric drier by removing the casing from the drying mechanism and effecting the drying of the material in the atmosphere. Obviously drying under atmospheric pressure 20 can also be effected by leaving the casing around the drying mechanism but cutting off the exhausting effect therefrom or opening the drying chamber to the atmosphere.

Inasmuch as the vapor outlet conduit leads 25 through the inner or front head which forms an immovable part of the casing it is possible to move the body and rear head of the casing for enclosing or uncovering the drum and associated parts without disturbing the 30 connections with the exhausting device and thus enable the apparatus to be used readily at will for drying under vacuum or atmospheric pressure to suit the requirements of different materials or conditions.

35. I claim as my invention:—

1. A drying apparatus comprising a drying drum, a support which is arranged at one end of said drum and which serves as the sole means upon which the drum is rotatably 40 mounted, supplying means mounted on said support for supplying the liquid to be dried to said drum, and removing means mounted on said support for removing the dried material from the drum.

45. 2. A drying apparatus comprising a drying drum, a support which is arranged at one end of said drum and which serves as the sole means upon which the drum is rotatably mounted, supplying means mounted on said support for supplying the liquid to be dried to said drum, removing means mounted on said support for removing the dried material from the drum, and a vacuum casing enclosing said drum, supplying means and removing means and detachably connected with said support.

50. 3. A drying apparatus comprising a drying drum, a support which is arranged at one end of said drum and which serves as the sole means upon which the drum is rotatably mounted, supplying means mounted on said support for supplying the liquid to be dried to said drum, removing means mounted on said support for removing the dried liquid therefrom, and a vacuum casing enclosing said drum, bearings, liquid supplying means, and dried liquid removing means and detachably connected with said standard.

dried material from the drum, and return 65 means mounted on said support and adapted to receive the excess liquid not taken up by said drum from the supplying means.

4. A drying apparatus comprising a drying drum, a support which is arranged at one 70 end of said drum and which serves as the sole means upon which the drum is rotatably mounted, supplying means mounted on said support for supplying the liquid, to be dried to said drum, removing means mounted on 75 said support for removing the dried material from the drum, return means mounted on said support and adapted to receive the excess liquid not taken up by said drum from the supplying means, and a vacuum casing enclosing 80 said drum, supplying means, removing means and return means and detachably connected with said support.

5. A drying apparatus comprising a drying drum, a support which is arranged at 85 one end of said drum and which serves as the sole means upon which the drum is rotatably mounted, supplying means mounted on said support for supplying to said drum the liquid to be dried, removing means mounted on said support for removing the dried material from 90 said drum, and a trough arranged below the drum and mounted on said support and adapted to receive the excess liquid supplied and not taken up by said drum. 95

6. A drying apparatus comprising a standard, a drying drum rotatably mounted on said standard, a casing mounted on said standard and enclosing said drum, a vapor outlet mounted on said standard independently of said casing and adapted to connect the space within the latter with an exhausting device, and means independent of said casing for supplying the liquid to be dried to said drum and carrying the excess liquid away 100 from the drum.

7. A drying apparatus comprising an upright support, a horizontal drying drum rotatably mounted on said support, means mounted on said support for supplying the liquid to be dried to said drum, means mounted on said support for removing the dried material from the drum, and including a discharge conduit extending through said support. 110

8. A drying apparatus comprising a horizontal rotary drying drum, an upright standard arranged at one end of said drum, an inboard bearing and an outboard bearing which rotatably support opposite ends of 120 said drum both of which are mounted on said standard, and means mounted on said standard for supplying the liquid to be dried to said drum and removing the dried liquid therefrom, and a vacuum casing enclosing said 125 drum, bearings, liquid supplying means, and dried liquid removing means and detachably connected with said standard.

9. A drying apparatus comprising a horizontal rotary drying drum, an upright standard arranged at one end only of said drum, an inboard bearing which is arranged on said standard and in which the inner end of said drum is journaled, an outboard bearing on which the outer end of said drum is journaled, means mounted on said standard for supplying the liquid to be dried to said drum and 5 removing the dried liquid therefrom, and an extension having a part arranged lengthwise of the drum on the under side thereof and connecting said outboard bearing with said standard and forming a trough which 10 catches the excess liquid supplied to said drum.

10. A drying apparatus comprising an upright support, an inboard bearing arranged on said support, a horizontal rotary drying 20 drum journaled at its inner end on said inboard bearing, an outboard bearing on which the outer end of said drum is journaled, means mounted on said support for supplying the liquid to be dried to said drum and removing 25 the dried liquid therefrom, and an extension having upper and lower longitudinal bars arranged above and below said drum and connected at their inner ends with said support and an upright post connecting the outer 30 ends of said bars and carrying said outboard bearing.

11. A drying apparatus comprising an upright support, an inboard bearing arranged on said support, a horizontal rotary drying 35 drum journaled at its inner end on said inboard bearing, an outboard bearing on which the outer end of said drum is journaled, means mounted on said support for supplying the liquid to be dried to said drum and removing 40 the dried liquid therefrom, and an extension having upper and lower longitudinal bars arranged above and below said drum and connected at their inner ends with said support and an upright post connecting the outer ends 45 of said bars and carrying said outboard bearing, said lower bar forming a trough which catches the excess liquid supplied to said drum.

12. A drying apparatus comprising a horizontal rotatable drying drum, an upright standard arranged at one end of said drum, an inboard bearing which is arranged on said standard and in which the inner end of said drum is journaled, an outboard bearing in 50 which the outer end of said drum is journaled, an extension supported solely on said standard including a longitudinal member connected at its inner end with said standard and a vertical member connected with the outer 55 end of said horizontal member and carrying said outboard bearing, means for supplying liquid to be dried to said drum including a feed pan arranged below the drum and supported at its opposite ends on said standard and upright member, and a vacuum casing en- 60

closing said drum, bearings, extension, and liquid supplying means and detachably connected with said standard.

13. A drying apparatus comprising a horizontal rotatable drying drum, an upright standard arranged at one end of said drum, an inboard bearing which is arranged on said standard and in which the inner end of said drum is journaled, an outboard bearing in which the outer end of said drum is journaled, an extension mounted solely on said standard including a longitudinal member connected at its inner end with said standard and a vertical member connected with the outer end of said horizontal member and carrying said outboard bearing, means for supplying liquid to be dried to said drum including a feed pan arranged below the drum and supported at its opposite ends on said standard and upright member, means for removing the dried material from said drum including a scraper supported at opposite ends on said standard and upright member, and a vacuum casing enclosing said drum, 70 bearings, extension, liquid supply means and dried material removing means and detachably connected with said standard. 75

14. A drying apparatus comprising a horizontal rotatable drying drum, an upright standard arranged at one end of said drum, an inboard bearing which is arranged on said standard and in which the inner end of said drum is journaled, an outboard bearing in which the outer end of said drum is journaled, an extension mounted solely on said standard and including a longitudinal member connected at its inner end with said standard and a vertical member connected with the outer end of said horizontal member and carrying said outboard bearing, means for supplying liquid to be dried to said drum including a feed pan arranged below the drum and supported at its opposite ends on said standard and upright member, means for removing the dried material from said drum including a scraper supported at opposite ends on said standards and upright member, and a conveyor which receives the dried material from said scraper and discharges it from the apparatus and which has a trough 100 mounted at opposite ends on said standard and said vertical member. 105

15. A drying apparatus comprising a horizontal rotatable drying drum, an upright standard arranged at the inner end of said drum, an inboard bearing which is arranged on said standard and in which the inner end of said drum is journaled, an outboard bearing in which the outer end of said drum is journaled, an extension mounted solely on said standard and including a longitudinal member connected at its inner end with said standard and a vertical member connected with the outer end of said horizontal member and carrying said outboard bearing, means for sup- 115 120 125 130

plying liquid to be dried to said drum including a feed pan arranged below the drum and supported at its opposite ends on said standard and upright member and a spreader which distributes the liquid over the drum and which is mounted at its opposite ends on said standard and said vertical member.

16. A drying apparatus comprising an upright support having an inboard bearing, a horizontal rotatable drying drum having its inner end journaled on said inboard bearing, an outboard bearing in which the outer end of said drum is journaled, an extension including a longitudinal member connected at its inner end with said support and a vertical member connected with the outer end of said horizontal member and carrying said outboard bearing, means for supplying liquid to be dried to said drum including a feed pan arranged below the drum and supported at its opposite ends on said support and upright member, and means mounted on said support for rocking said feed pan.

17. A drying apparatus comprising a horizontal rotatable drying drum, an upright standard arranged at one end of said drum, an inboard bearing which is arranged on said standard and in which the inner end of said drum is journaled, an outboard bearing in which the outer end of said drum is journaled, an extension mounted solely on said standard and including a longitudinal member connected at its inner end with said standard and a vertical member connected with the outer end of said horizontal member and carrying said outboard bearing, means for supplying liquid to be dried to said drum including a feed pan arranged below the drum and supported at its opposite end on said standard and upright member, a spreader which distributes the liquid over the drum and which is mounted at its opposite ends on said standard and said vertical member, and means mounted on said standard for adjusting the spreader relatively to said drum.

18. A drying apparatus comprising a horizontal rotary drying drum, an upright standard arranged at one end of said drum and forming the sole support therefor, means mounted solely on said standard for supplying the liquid to be dried to said drum, means mounted solely on said standard for removing the dried material from the drum, including a knife which is movable toward and from the drum, means mounted solely on said standard for adjusting the position of said knife relatively to the scraper from the exterior of the apparatus, and a vacuum casing enclosing said drum, liquid supplying means, dried material removing means and adjusting means and detachably connected with said standard.

19. A drying apparatus comprising a main frame, an enclosing casing having a stationary head mounted on the frame, a cylindrical

body movable toward and from said stationary head and a head mounted on said body and movable therewith, a drying drum rotatably mounted on said stationary head and adapted to be enclosed by said casing and to be uncovered by moving said body and the head thereon away from said stationary head; and means independent of said body mounted solely on said standard within the perimeter of the stationary head for supplying liquid to be dried to said drum and removing the dried material therefrom.

20. A drying apparatus comprising a frame, having a horizontal base and a standard rising from the base, a stationary casing head arranged on said standard, a rotary drying drum rotatably mounted on said stationary head, a cylindrical casing body movably mounted on said standard and adapted to surround said drum and to engage one of its ends with said stationary head, a head arranged on the opposite end of the casing body and movable therewith; and means independent of said body and mounted solely on said standard within the perimeter of the stationary head for supplying liquid to be dried to said drum and removing the dried material therefrom.

21. A drying apparatus comprising a frame having a horizontal base and a standard rising from the base, a stationary casing head arranged on said standard, a rotary drying drum rotatably mounted on said stationary head, a cylindrical casing body adapted to surround said drum and to engage one of its ends with said stationary head, a head arranged on the opposite end of the casing body and movable therewith, means for movably supporting said casing body and the head thereon on said base; and means independent of said body and mounted solely on said standard within the perimeter of the stationary head for supplying liquid to be dried to said drum and removing the dried material therefrom.

22. A drying apparatus comprising a frame having a horizontal base and a standard rising from the base, a stationary casing head arranged on said standard, a rotary drying drum rotatably mounted on said stationary head, a cylindrical casing body adapted to surround said drum and to engage one of its ends with said stationary head, a head arranged on the opposite end of the casing body and movable therewith, means for movably supporting said casing body and the head thereon on said base, comprising a track arranged on said base, and wheels mounted on said body and running on said track; and means independent of said body and mounted solely on said standard within the perimeter of the stationary head for supplying liquid to be dried to said drum and removing the dried material therefrom.

23. A drying apparatus comprising a

- frame having a horizontal base and a standard rising from the base, a stationary casing head arranged on said standard, a rotary drying drum rotatably mounted on said stationary head, a cylindrical casing body adapted to surround said drum and to engage one of its ends with said stationary head, a head arranged on the opposite end of the casing body and movable therewith, means 5 for movably supporting said casing body and the head thereon on said base, comprising a track arranged on said base, and wheels mounted on said body and running on said track; means for moving said body and movable head toward and from said stationary head; and means independent of said body and mounted solely on said standard within the perimeter of the stationary head for supplying liquid to be dried to said drum and 10 removing the dried material therefrom.
24. A drying apparatus comprising a frame having a horizontal base and a standard rising from the base, a stationary casing head arranged on said standard, a rotary drying drum rotatably mounted on said stationary head, a cylindrical casing body adapted to surround said drum and to engage one of its ends with said stationary head, a head arranged on the opposite end of the casing body 15 and movable therewith, means for movably supporting said casing body and the head thereon on said base, comprising a track arranged on said base, and wheels mounted on said body and running on said track; means for moving said body and movable head toward and from said stationary head comprising a gear rack mounted on the lower part of said body, a gear pinion mounted on said base and meshing with said gear rack, and means 20 for actuating said gear pinion; and means independent of said body and mounted solely on said standard within the perimeter of the stationary head for supplying liquid to be dried to said drum and removing the dried material therefrom.
25. A drying apparatus comprising a frame having a base and a standard rising from the base, an enclosing casing having a stationary front head mounted on said standard, a movable cylindrical body adapted to engage and disengage its front end with said front head, and a head arranged on the rear end of said body; a drying drum arranged within said casing and rotatably mounted on said front head, means for coupling and uncoupling said front head and the front end of said casing body; and means independent of said body and mounted solely on said standard within the perimeter of the stationary head for supplying liquid to be dried to said drum and removing the dried material therefrom.
26. A drying apparatus comprising a frame having a base and a standard rising from the base, an enclosing casing having a 50 stationary front head mounted on said standard, a movable cylindrical body adapted to engage and disengage its front end with said front head, and a head arranged on the rear end of said body; a drying drum arranged within said casing and rotatably mounted on said front head, means for coupling and uncoupling said front head and the front end of said casing body; and means independent of said body and mounted solely on said standard within the perimeter of the stationary head for supplying liquid to be dried to said drum and removing the dried material therefrom.
27. A drying apparatus comprising a frame having a base and a standard rising from the base, an enclosing casing having a stationary front head mounted on said standard, a movable cylindrical body adapted to engage and disengage its front end with said front head, and a head arranged on the rear end of said body; a drying drum arranged within said casing and rotatably mounted on said front head, means for coupling and uncoupling said front head and the front end of said casing body comprising a plurality of coupling bolts arranged on the periphery of said front head and each provided with a head at its rear end, a locking ring movable circumferentially on said casing, and a plurality of wedges arranged on said locking ring and each adapted to engage with the back of the head on one of said locking bolts; and means for supplying the liquid to be dried to said drum and removing the dried material therefrom.
28. A drying apparatus comprising a frame having a base and a standard rising from the base, an enclosing casing having a stationary front head mounted on said standard, a movable cylindrical body adapted to engage and disengage its front end with said front head, and a head arranged on the rear end of said body; a drying drum arranged within said casing and rotatably mounted on said front head; means for coupling and uncoupling said front head and the front end of said casing body comprising a plurality of coupling bolts arranged on the periphery of said stationary head and each having a head at its rear end, a locking ring rotatable circumferentially on said body and provided with a plurality of key-hole slots, the wide part of each slot permitting the passage of the head of a coupling bolt and the narrow part thereof being adapt- 130

ed to receive the shank of a coupling bolt and a plurality of wedges mounted on said ring and each adapted to engage the back of the head of one of said coupling bolts; and means 5 for supplying the liquid to be dried to said drum and removing the dried material therefrom.

29. A drying apparatus comprising a frame having a base and a standard rising from the 10 base, an enclosing casing having a stationary front head mounted on said standard, a movable cylindrical body adapted to engage and disengage its front end with said front head, and a head arranged on the rear end of said body; a drying drum arranged within said casing and rotatably mounted on said front head; means for coupling and uncoupling said front head and the front end of said casing body comprising a plurality of coupling bolts 15 arranged on the periphery of said stationary head and each having a head at its rear end, a locking ring rotatable circumferentially on said body and provided with a plurality of key-hole slots, the wide part of each slot permitting the passage of the head of a coupling 20 bolt and the narrow part thereof being adapted to receive the shank of a coupling bolt, a plurality of wedges mounted on said ring and each adapted to engage the back of the head 25 of one of said coupling bolts, and a coupling flange arranged on the body and engaging the front side of said ring and provided with a plurality of openings each of which receives the head and shank of one of said coupling bolts; and means for supplying the liquid to be dried to said drum and removing the dried material therefrom.

30. A drying apparatus comprising a frame having a base and a standard rising 40 from the base, an enclosing casing having a stationary front head mounted on said standard, a movable cylindrical body adapted to engage and disengage its front end with said front head, and a head arranged 45 on the rear end of said body; a drying drum arranged within said casing and rotatably mounted on said front head; means for coupling and uncoupling said front head and the front end of said casing body comprising 50 a plurality of coupling bolts arranged on the periphery of said stationary head and each having a head at its rear end, a locking ring rotatable circumferentially on said body and provided with a plurality of key-hole slots, 55 the wide part of each slot permitting the passage of the head of a coupling bolt and the narrow part thereof being adapted to receive the shank of a coupling bolt, a plurality of wedges mounted on said ring and each 60 adapted to engage the back of the head of one of said coupling bolts, a coupling flange arranged on the body and engaging the front side of said ring and provided with a plurality of openings each of which receives the 65 head and shank of one of said coupling bolts,

and a plurality of clips secured to said flange and engaging with the rear side of said locking ring; and means for supplying the liquid to be dried to said drum and removing the dried material therefrom.

31. A drying apparatus comprising a stationary main frame having a standard, an enclosing casing having a stationary front head arranged on said standard and provided with a bearing, a longitudinally movable 70 body adapted to be connected and disconnected at its front end with said front head and a rear head arranged on said body and movable longitudinally therewith; a rotary drum arranged within said casing and having a trunnion journaled in the bearing of said front head; and means independent of said movable body mounted solely on said standard within the perimeter of the stationary head for supplying liquid to be dried 75 to said drum and removing the dried material therefrom.

32. A drying apparatus comprising a stationary main frame having a standard, an enclosing casing having a stationary front 80 head arranged on said standard and provided with a bearing, a longitudinally movable body adapted to be connected or disconnected at its front end with said front head and a rear head arranged on said body 85 and movable longitudinally therewith, a rotary drum arranged within said casing and having a trunnion journaled in the bearing of said front head; means for rotating said drum connected with said trunnion on the exterior of said casing; and means independent of said body and mounted solely on said frame for supplying liquid to be dried to 90 said drum and removing the dried material therefrom.

33. A drying apparatus comprising a stationary main frame having a standard, an enclosing casing having a stationary front head arranged on said standard and provided with a bearing, a longitudinally movable 95 body adapted to be connected and disconnected at its front end with said front head and a rear head arranged on said body and movable longitudinally therewith, a rotary drum arranged within said casing and having a front trunnion journaled in the bearing of said front head and also provided with a rear trunnion, a rear bearing which is arranged within the rear part of said casing 100 and mounted on said front head and in which the rear trunnion of said drum is journaled; and means independent of said body and mounted solely on said frame for supplying liquid to be dried to said drum and removing the dried material therefrom.

34. A drying apparatus comprising a stationary main frame having a standard, an enclosing casing having a stationary front head arranged on said standard and provided with a bearing, a longitudinally movable 110

body adapted to be connected and disconnected at its front end with said front head and a rear head arranged on said body and movable longitudinally therewith, a rotary drum arranged within said casing and having a front trunnion journaled in the bearing of said front head and also provided with a rear trunnion, a rear bearing which is arranged in the rear part of said casing and 5 in which the rear trunnion of said drum is journaled, an upright column carrying said rear bearing, a beam arranged lengthwise within said casing and connecting said column with said front casing head; and means 10 mounted solely on said frame for supplying the liquid to be dried to said drum and removing the dried material therefrom.

35. A drying apparatus comprising a stationary main frame having a standard, an enclosing casing having a stationary front head arranged on said standard and provided with a bearing, a longitudinally movable body adapted to be connected and disconnected at its front end with said front head 20 and a rear head arranged on said body and movable longitudinally therewith, a rotary drum arranged within said casing and having a front trunnion journaled in the bearing of said front head and also provided with 25 a rear trunnion, a rear bearing which is arranged in the rear part of said casing and in which the rear trunnion of said drum is journaled, an upright column carrying said rear bearing, beams arranged lengthwise in the 30 casing above and below said drum and connecting the upper and lower ends of said column with the corresponding parts of said front head; and means mounted solely on said frame for supplying the liquid to be dried 35 to said drum and removing the dried material 40 therefrom.

36. A drying apparatus comprising a frame having a standard, an enclosing casing having a stationary front head arranged 45 on said standard, a cylindrical body movable longitudinally and adapted to be connected and disconnected at its front end with said front head, and a rear head arranged on the rear end of said body and movable longitudinally therewith, a support arranged in the 50 rear part of said casing and connected with said front head, a drying drum arranged within said casing and rotatably mounted at its front and rear ends on said front head 55 and rear support; and means mounted solely on said frame for supplying the liquid to be dried to said drum and removing the dried material therefrom.

37. A drying apparatus comprising a 60 frame having a standard, an enclosing casing having a stationary front head arranged on said standard, a cylindrical body movable longitudinally and adapted to be connected and disconnected at its front end with said 65 front head, and a rear head arranged on the

rear end of said body and movable longitudinally therewith, an upright rear column arranged in the rear part of said casing; a rotary drying drum arranged in said casing and rotatably mounted at its front and rear 70 ends on said front head and rear column, a longitudinal beam arranged below the drum and connected at its front and rear ends with said front head and rear column and provided in its upper side with a trough which 75 is mounted solely on said frame; feeding means which are arranged above the trough for feeding liquid to be desiccated to said drum and from which the excess liquid overflows into said trough.

38. A drying apparatus comprising a frame having a standard, an enclosing casing having a stationary front head arranged on said standard, a cylindrical body movable longitudinally and adapted to be connected and disconnected at its front end with said front head, and a rear head arranged on the rear end of said body and movable longitudinally therewith, an upright rear column arranged in the rear part of said casing, a rotary drying drum arranged in said casing and rotatably mounted at its front and rear 80 ends on said front head and rear column, a longitudinal beam arranged below the drum and connected at its front and rear ends with said front head and rear column and provided in its upper side with a trough which 85 is mounted solely on said frame, feeding means which are arranged above the trough for feeding liquid to be desiccated to said drum and from which the excess liquid overflows into said trough; and a knife mounted on said beam along one side of said trough and adapted to scrape the dried material from 90 said drum.

39. A drying apparatus comprising a frame having a standard, an enclosing casing having a stationary front head arranged on said standard, a cylindrical body movable longitudinally and adapted to be connected and disconnected at its front end with said front head, and a rear head arranged on the rear end of said body and movable longitudinally therewith, an upright rear column arranged in the rear part of said casing, a rotary drying drum arranged in said casing and rotatably mounted at its front and rear 100 ends on said front head and rear column, a longitudinal beam arranged below the drum and connected at its front and rear ends with said front head and rear column and provided in its upper side with a trough which 105 is mounted solely on said frame, feeding means which are arranged above the trough for feeding liquid to be desiccated to said drum and from which the excess liquid overflows into said trough; and a knife mounted on said beam along one side of said trough and adapted to scrape the dried material from 110 said drum.

40. A drying apparatus comprising a frame having a standard, an enclosing casing having a stationary front head arranged on said standard, a cylindrical body movable longitudinally and adapted to be connected and disconnected at its front end with said front head, and a rear head arranged on the rear end of said body and movable longitudinally therewith, an upright rear column arranged in the rear part of said casing, a rotary drying drum arranged in said casing and rotatably mounted at its front and rear 115 ends on said front head and rear column, a longitudinal beam arranged below the drum and connected at its front and rear ends with said front head and rear column and provided in its upper side with a trough which 120 is mounted solely on said frame, feeding means which are arranged above the trough for feeding liquid to be desiccated to said drum and from which the excess liquid overflows into said trough; and a knife mounted on said beam along one side of said trough and adapted to scrape the dried material from 125 said drum; and a conveyor arranged within the 130

casing on one side of said trough and adapted to receive the dried material scraped from the drum by said knife.

40. A drying apparatus comprising a frame having a standard, an enclosing casing having a stationary front head arranged on said standard, a cylindrical body movable longitudinally and adapted to be connected and disconnected at its front end with 5 said front head, and a rear head arranged on the rear end of said body and movable longitudinally therewith, an upright rear column arranged in the rear part of said casing, a rotary drying drum arranged in 10 said casing and rotatably mounted at its front and rear ends on said front head and rear column, a longitudinal beam arranged below the drum and connected at its front and rear ends with said front head and rear column and 15 provided in its upper side with a trough which is mounted solely on said frame, feeding means which are arranged above the trough for feeding liquid to be desiccated to said drum and from which the 20 excess liquid overflows into said trough, a knife mounted on said beam along one side of said trough and adapted to scrape the dried material from said drum; and a conveyor arranged within the casing on one side 25 of said trough and adapted to receive the dried material removed from the drum by said knife, said conveyor having a trough supported on said front head and said column.

30

35. 41. A drying apparatus comprising a frame having a standard, an enclosing casing having a stationary front head arranged on said standard, a cylindrical body movable longitudinally and adapted to be connected 40 and disconnected at its front end with said front head, and a rear head arranged on the rear end of said body and movable longitudinally therewith, an upright rear column arranged in the rear part of said casing, a rotary drying drum arranged in 45 said casing and rotatably mounted at its front and rear ends on said front head and rear column, a longitudinal beam arranged below the drum and connected at its front and rear ends with said front head and rear column and 50 provided in its upper side with a trough mounted solely on the standard within the perimeter of the stationary head, feeding means which are arranged above the trough for feeding liquid to be desiccated to said drum and from which the excess liquid overflows into said trough, a knife mounted on 55 said beam along one side of said trough and adapted to scrape the dried material from said drum; and means for adjusting said knife relatively to said drum including a longitudinal rock shaft journaled at its front and rear ends in said front head and rear column and operatively connected with said knife.

distributing pipe and receiving liquid therefrom and presenting the liquid to the under-side of said drum.

42. A drying apparatus comprising a frame having a standard, an enclosing casing having a stationary front head arranged on said standard, a cylindrical body movable longitudinally and adapted to be connected and disconnected at its front end with said front head, and a rear head arranged on the rear end of said body and movable longitudinally therewith, an upright rear column arranged in the rear part of said casing, a rotary drying drum arranged in 70 said casing and rotatably mounted at its front and rear ends on said front head and rear column, a longitudinal beam arranged below the drum and connected at its front and rear ends with said front head and rear column and provided in its upper side with a trough which is mounted solely on said frame, feeding 75 means which are arranged above the trough for feeding liquid to be desiccated to said drum and from which the excess liquid overflows into said trough; and a liquid spreader supported at its front and rear ends on said 80 front head and rear column.

43. A drying apparatus comprising a frame having a standard, an enclosing casing having a stationary front head arranged on said standard, a cylindrical body movable 90 longitudinally and adapted to be connected and disconnected at its front end with said front head, and a rear head arranged on the rear end of said body and movable longitudinally therewith, an upright rear column arranged in the rear part of said casing, a rotary drying drum arranged in 95 said casing and rotatably mounted at its front and rear ends on said front head and rear column, a longitudinal beam arranged below the drum and connected at its front and rear ends with said front head and rear column and 100 provided in its upper side with a trough mounted solely on the standard within the perimeter of the stationary head, feeding 105 means which are arranged above the trough for feeding liquid to be desiccated to said drum and from which the excess liquid overflows into said trough, a knife mounted on said beam along one side of said trough and 110 adapted to scrape the dried material from said drum; and means for adjusting said knife relatively to said drum including a longitudinal rock shaft journaled at its front and rear ends in said front head and rear column and operatively connected with said knife.

HENRY D. MILES.
